UNITED STATES PATENT OFFICE.

AMY M. ESHLEMAN, OF LANCASTER, PENNSYLVANIA.

DESIGN FOR A DOLL.

Application filed March 8, 1922. Serial No. 1,078. Term of patent 7 years.

To all whom it may concern:

Be it known that I, AMY M. ESHLEMAN, a citizen of the United States, residing at Lancaster, in the county of Lancaster and State of Pennsylvania, have invented a new, original, and ornamental Design for Dolls, of which the following is a specification, reference being had to the accompanying drawing, forming part thereof.

The figure is a front view of the doll, showing my new design.

I claim:

The ornamental design for a doll, as shown.

AMY M. ESHLEMAN.
